SIGMUND JOSEPH PENTLER AND OTTO R. SHORT, OF WAUSAU, WISCONSIN.

METHOD OF MAKING SHOES.

1,382,625.

Specification of Letters Patent.

Patented Oct. 22, 1918.

Application filed March 30, 1913. Serial No. 235,826.

To all whom it may concern:—
Be it known that we, SIGMUND JOSEPH PENTLER and OTTO R. SHORT, citizens of the United States, and residents of Wausau, in the county of Marathon and State of Wisconsin, have invented certain new and useful Improvements in Methods of Making Shoes; and we do hereby declare that the following is a full, clear, and exact description thereof.

Our invention relates to improvements in the method of manufacturing stitched down shoes and specifically in the manner of securing the inner sole to the middle sole.

Up to the present time it has been impossible to fasten at the shank the inner sole and lining of a stitched-down shoe to the middle sole or doubler, in a satisfactory manner. Ordinarily the inner sole of a stitched-down shoe is fastened to the middle sole with cement or other adhesive material to prevent the same from becoming detached. This has proven very unsatisfactory, as in many instances after the shoe has been subjected to wear the inner sole becomes loose at the shank and permits the lining to become detached at the same place. Numerous attempts have been made to secure the inner sole as well as the lining to the middle sole by driving tacks through the several soles at the shank portion and clenching these on the inside. This method is unsightly and objectionable due to the fact that the clenched portions of the tacks are exposed and come into direct contact with the foot. It is therefore the object of the present invention to provide means for clenching the tacks or other fastening devices before reaching the inside of the shoe.

The invention in one practical form in which it may be embodied is illustrated in the accompanying drawings, in which:—

Figure 1 represents a side elevational view partly in section of a shoe in the process of manufacture under our improved method.

Fig. 2 is a perspective view of a double insole such as is shown in Fig. 1, and

Fig. 3 is a similar view of a sock lining having a reinforcing or extra shank piece.

Referring now more particularly to the drawings wherein similar reference characters indicate like parts throughout the views, the numeral 1 denotes a shoe upper in which is disposed a last 2 and to which is being applied by our improved method an inner sole comprising a sock lining 3 and insole 4

and a middle sole 5. The sock lining and inner sole 3 and 4 respectively, together form a double inner sole as shown in Fig. 2.

In a stitched-down type of shoe the inner sole, that is to say the lining 3 and insole 4 are identical in contour with the bottom of the last 2, while the middle sole 5 is considerably larger and has the upper lasted and stitched thereto except at the heel seat where the upper is drawn over and lasted by means of tacks. Before stitching the upper to the middle sole it is necessary to position the sole with respect to the last by means of tacks or nails 6 which are disposed through the shank of said middle sole and the similar portion of the insole 4.

Ordinarily these tacks extend into the last 2 and through the sock lining 3. The invention, however, as hereinbefore set forth is to clenche said tacks in the insole 4 as shown in Fig. 1. This is carried out in the form of a double inner sole shown in Figs. 1 and 2 by providing the central portion of the shank of the insole 4 with one or more transversely extending slits 7. These slits are formed preferably before the sock lining 3 and the insole 4 are stitched together as at 8. The form of the invention illustrated in Fig. 3 is for a shoe in which the inner sole is formed of a sock lining 3' and a reinforcing shank piece 4', the latter being secured together as at 8' to the former. The shank piece 4' is in fact a portion of an insole and in so far as the invention is concerned is the equivalent of the insole 4. Said shank piece has a transversely extending centrally disposed slit 7' which, as in the case of the slits 7 is disposed between the rows of stitching 8'.

The slits 7 and 7' are adapted to permit an elongated slightly longitudinally curved clenching plate 9 to be inserted therein for engagement with the inner surface of the insole 4 or shank piece 4', such insertion obviously being made after the inner soles, which may include either the sock lining 3 and insole 4 or the sock lining 3' and shank piece 4', are secured to the shoe upper 1. The tacks 6 may now be driven through the middle sole and the insole 4 or shank piece 4' and readily clenched. When the tacking is completed the clenching plate is readily removable by inserting the finger through a ring 10 formed at one end thereof and withdrawing the plate.

When two slits are formed in the insole

as shown in Fig. 2, the one nearest the toe preferably receives the clenching plate first and when all of the necessary tacks have been placed between said slit and said toe 5. the plate is removed and re-inserted through the other slit whereupon additional tacks may be driven through the middle sole between the two slits.

From the foregoing description it will be 10 seen that by our improved method we are enabled to secure the inner sole of a shoe to the middle sole by means of tacks or other fastening devices and at the same time make the inside of the shoe free from exposed 15 clenched portions of the tacks or other fastening means. Furthermore it will be seen that by constructing the inner sole of two layers, namely: the sock lining 3 and insole 4, the insole can be constructed of any 20 suitable material while a very cheap material such as canvas, cork or other substitute for leather can be used for the insole 4 as the same is not exposed at any portion.

We claim as our invention:—
25 1. The herein described method of manufacturing shoes which consists in forming a slit in an inner sole, securing said inner sole to a lining sole, inserting a clenching plate

through said slit to dispose the same between said soles, nailing a middle sole to the insole 30 and clenching the nails on said plate, and thereafter removing said plate.

2. The herein described method of manufacturing stitch-down shoes which consists in forming a double layer inner sole with 35 prepared slits in one layer for receiving a clenching tool to be disposed between the layers, inserting the tool in one of the slits, applying a middle sole to the inner sole and driving fastening members through the middle sole and that portion of the layer of the inner sole covered by the clenching tool and clenching said members against the tool, in withdrawing the tool and inserting it in a second slit to cover another portion of 40 the layer of the inner sole, in driving fastening members through the middle sole and inner sole layer and clenching them against the tool and then removing the tool.

In testimony that we claim the foregoing 50 we have hereunto set our hands at Wausau, in the county of Marathon, and State of Wisconsin.

SIGMUND JOSEPH PENTLER.
OTTO R. SHORT.
